(57) **CLAIM**

I claim the ornamental design for a top load CDG player, as shown and described.

DESCRIPTION

FIG. 1 is a front elevation view of the top load CDG player showing my novel design;

FIG. 2 is a rear plan view thereof;

FIG. 3 is a left side elevation view thereof;

FIG. 4 is a right side elevation view thereof;

FIG. 5 is a top plan view thereof;

FIG. 6 is a bottom plan view thereof; and

FIG. 7 is a perspective view thereof; and,

FIG. 8 is a perspective view thereof with disk lid open.

The broken lines showing in FIG. 8 illustrate an external music player and form no part of the claimed design.
